UNITED STATES PATENT OFFICE

HARRY E. NORVIEL, OF ANDERSON, INDIANA, ASSIGNOR TO DELCO-REMY CORPORATION, OF DAYTON, OHIO, A CORPORATION OF DELAWARE

SWITCH AND COIL UNIT

Application filed December 21, 1927. Serial No. 241,679.

This invention relates to ignition switch and coil units for automotive vehicles and one of the objects of the invention is to produce at low cost a lock switch and a coil unit which is rugged in construction and reliable in operation.

A further object of the invention is to provide a unit comprising a plurality of ignition coils and a single key operated switch for controlling the connection of the coil with a current source.

Further objects and advantages of the present invention will be apparent from the following description, reference being had to the accompanying drawings, wherein a preferred form of embodiment of the present invention is clearly shown.

In the drawings:

Fig. 1 is a front view of a unit embodying the present invention.

Fig. 2 is a side view, partly in longitudinal section, the section being taken on the line 2—2 of Fig. 1.

Fig. 3 is a view looking in the direction of the arrow 3 in Fig. 2, the switch case being removed.

Fig. 4 is a fragmentary sectional view taken principally on the line 4—4 of Fig. 1.

Fig. 5 is a fragmentary sectional view taken on the line 5—5 of Fig. 1.

Fig. 6 is a fragmentary sectional view looking in the direction of arrow 6 of Fig. 5.

Fig. 7 is a side view, partly in longitudinal section, of a modified form of lock-switch and coil unit embodying the present invention.

Fig. 8 is a wiring diagram of the circuits included in the form shown in Fig. 2.

The ignition coil used in both forms of the invention may be any suitable ignition coil having a non-conducting end cover which may serve as a support for switch contacts.

One suitable ignition coil is that shown in the copending application of William A. Chryst and Ralph I. Bates Serial No. 236,552, filed Nov. 29, 1927, (DR—3436). This coil comprises a tubular metallic case 20 which cooperates with a non-conducting end cover 21 and a non-conducting end cover 22 to enclose the windings and magnetic circuit members of the coil and also the leads

from the coils to certain contacts carried by the covers. The coil comprises a secondary winding 23 wrapped upon a non-conducting tube 24 and covered by non-conducting wrapping 25. The tube 24 receives a central magnetic circuit provided by a bundle of iron wires 26, which extend beyond the end of the margins 27 of the paper strips which insulate the layers of secondary turns. The core 26 terminates short of the left hand end of tube 24 and the left hand end of the paper margins 28. The end member 22 is provided with an annular flange 29 which defines a recess 30 for receiving a non-conducting disc 31 and portions of the wrapping 25, the paper margins 28 and the tube 24, and a non-conducting plug 32 located within the tube 24. In this way, the left end of the secondary winding is supported against lateral movement. The cover member 21 is provided with a flange 33 for receiving the right hand end of the wrapping 25, a portion of the paper margins 27, and of the tube 24 and of the core wires 26. Thus the right hand end of the secondary coil 23 and of the core 26 is supported against lateral movement. A non-conducting tube 34 upon which the primary coil 35 is wound is confined between the flanges 29 and 33 to prevent lateral and longitudinal movement thereof. There is a space between the tubes 34 and 25 in order that the hydrolene 36, introduced at either end of the case 20 before the covers are attached, may flow between the primary and secondary coils. The primary winding 35 is surrounded by a tube 37 upon which is wound a strip of magnetic sheet material, the turns of which are insulated by sheet insulating material. The wrapping of magnetic material and insulating material about the tube 37 is indicated by numeral 38.

The end cover 21 is provided with a hole 40 for receiving the outside lead 41 of the secondary 23 and the inside lead 42 of the primary 35. These lead wires are attached by soldering to a terminal plate 43 attached to the end cover 21 and receiving a terminal screw 44. The cover 21 is provided with a hole 45 for receiving a wire 46 which is attached to a terminal plate 47 receiving a ter-

5 minal screw 48. The other end of the wire 46 is led through a hole 49 provided in the end cover 22 and is connected with rivet 50 having its head 51 embedded in the insulating material 22 which is preferably a molding compound which is molded around the rivet 50. The cover 22 is provided with an insert-rivet 52 to which a wire 53 is attached, this wire passing through a hole 54 in the 10 cover 22 and connected with the outside in-turn of the primary 35.

15 The construction of the upper coil shown in Fig. 2 is the same as the lower, but certain connections shown in the lower coil are omitted in the upper coil. The cases 20 of the coils are welded to metal collars 60 provided with ears 61 which are attached by rivets 62 to a coil mounting plate 63. The coil mounting plate 63 is provided with a 20 number of holes as shown in Fig. 3, for receiving screws 65 having threaded engagement with the flange 66 of a switch case member 67 which cooperates with the plate 63 to enclose the switch and lock and the electrical 25 connections between the switch and the ignition coils. The front wall 70 of the switch case 67 carries a tubular boss 71 in which is fitted a tube 72 cooperating with the boss 71 to provide a guide for the barrel 73 of a 0 conventional automobile-type tin-tumbler lock. The details of this lock are not shown but it will be understood by those skilled in this art by turning the proper key 74 which is received by a key cylinder 75, rotatable in 35 the barrel 73, a locking bolt 76 will be retracted against a pressure of a compression spring 77 so that the end of the bolt 76 will be located with the flush of the exterior of the barrel 73. The switch case 67 provides recesses 78 and 79 for receiving the bolt 76 in either position of the barrel 73. The barrel 73 is prevented from turning and its movement is limited by providing the barrel with a groove 80 which receives a pin 81 extending 40 from the grooved plug 82 threadedly engaging the case 67. The movement of the barrel 73 is used in operating a switch for controlling the flow of current through the 45 ignition coils.

50 The ignition switch comprises a pair of resilient blades 84 and 85 which are normally held apart by an L-shaped non-conducting support 86 carrying a contact rivet 87 engageable with the blades 84 and 85 simultaneously. The contact support 86 is attached by rivets 88 to a bracket 89 attached by a screw 90 to the barrel 75 and prevented from rotating by pin 81. The contact blade 84 is attached by rivets 92 to a bracket 93 which 55 is attached to the conducting rivet 50 and to a similar rivet 50a provided by an insert in the cover plate 22 as shown particularly in Fig. 3. The contact plate 85 is similarly supported by a bracket 94 which is attached 60 to the conducting rivet 52 and by similar 65

rivet 52a to the end cover 22. The upper coil shown in Fig. 2 is provided with a similar bracket 94 attached by the rivets 52 and 52a. The location of the upper coil relative to the mounting plate 63 is the reverse of the relation of the mounting plate 63 and the lower coil. That is, the bracket 94 of the lower coil is uppermost while the bracket 94 of the upper coil is lowermost as shown in Fig. 3. The two brackets 94 are connected by a strap 70 75 75 attached at its ends by the screws 96. The rivets 50 and 50a of the upper coil perform no function, but are present merely because the same cover 22 is used for both coils.

80 When the lock mechanism is in the position shown in the drawings the switch contacts 84 and 85 will be separated by the non-conducting contact support 86. To close the switch, the key 74 is turned in order to retract the bolt 76 from the recess 78 thereby 85 releasing a spring 100 which, by reason of its location between the end cover 22 and the barrel 73, causes the barrel 73 to be moved toward the left until the right hand end of the groove 80 is engaged by the end of the pin 81. 90 In this position of the barrel the key 74 may be released to permit the bolt 76 to move into the recess 79 so that the key may be withdrawn if desired. Movement of the barrel 73 as described will cause the contact rivet 87 95 to move into engagement with the contact blades 84 and 85, thereby closing the switch.

100 Referring to Fig. 8, when the switch is closed the following ignition circuit will be established: battery 110 grounded at 111 and connected with coil terminal plate 47, wire 46 within the coil, contact bracket 93, contact 84, contact 87, contact 85, strap 95 connected with both brackets 94, and parallel primary coil circuits each circuit including the outside lead 53 of the primary, the primary coil 35, the inside lead 42, coil terminal 43, an ignition circuit breaker terminal 112, a movable interrupter contact 113 and a stationary interrupter contact 114 grounded at 115. 105 Each circuit breaker lever includes a rubbing block 116 operated by a cam 117.

110 In this way a single switch controls the primary circuit of both ignition coils. To open the switch the barrel 73 is pushed inwardly preferably without using a key; and when the bolt 76 has been moved adjacent the recess 78 it will spring into this recess to lock the barrel 73 in switch-open position against the compression of the spring 100. The spring 100 is retained in position by locating one of its ends in a recess 101 provided by the barrel 73 and by placing the spring around a cylindrical lug 102 integral with the end cover 22.

115 The outside lead 41 of the secondary coil 23 of each coil is grounded through the timer as shown in Fig. 8 by connecting the lead 41 with the coil terminal plate 43. The inside lead 105 of each secondary coil 23 is connect- 120 125 130

ed with the core 26 and the core 26 is connected by a nail 106 with a conducting sleeve 107 which receives the terminal clip of a wire leading to a distributor not shown.

5 Referring to Fig. 7, in case it is desired to use but one of the ignition coils which have been described with a key-operated ignition switch, the coil base 20 is welded to a sleeve 120 having tangs 121 received by suitable notches in a switch frame 122 and bent over against the front of the frame 122. The frame 122 cooperates with the sleeve 120 to provide a housing for the switch. The construction of the switch and the key controlled device for operating its movable contact is the same as described in connection with the switch shown in Fig. 2. The connections between the ignition coil and the switch are the same as between the switch and the lower 20 coil of Fig. 2.

The present invention therefore provides a rugged and compact structure involving a plunger-type key operated device for operating the switch; provides a construction permitting the use of one or more identical ignition coils with the same switch, and provides for using the same switch parts regardless of the number of ignition coils included in the switch and coil unit.

20 While the form of embodiment of the present invention, as herein disclosed, constitutes a preferred form, it is to be understood that other forms might be adopted, all coming within the scope of the claims which follow.

What is claimed is as follows:

1. A lock-switch comprising, a switch case, a lock barrel slidably supported by the front wall of the case, terminal brackets within the case, contacts attached to the brackets and extending alongside the barrel, and means actuated by the barrel for electrically connecting the contacts.

45 2. A lock-switch comprising, a switch case, a lock barrel slidably supported by the case, terminal brackets within the case and attached to the back wall thereof, contacts attached to the brackets and extending alongside the barrel, and a movable contact member carried by the barrel for bridging the other contacts.

50 3. A lock-switch comprising, a switch case, a lock barrel slidably supported by the case, a spring bearing against a wall of the case and the end of the barrel within the case for urging the barrel in one direction, a key controlled latch for holding the barrel in one position against the force exerted by the spring, a switch actuating member attached to said end of the barrel, and switch contacts extending alongside the barrel within the case and cooperating with the actuating member to open and close an electric circuit.

55 4. A lock-switch comprising, a switch case, a lock barrel slidably supported by the front

wall of the case, a pair of spring blade contacts attached to the back wall of the case and extending toward the front wall and alongside the barrel, and a member attached to the barrel and extending laterally from the barrel and alongside the barrel and cooperating with the blade contacts to open and close an electric circuit.

5. A lock-switch comprising, a switch case, a lock barrel slidably supported by the front wall of the case, a pair of spring blade contacts attached to the back wall of the case and extending toward the front wall and alongside the barrel, a non-conducting plate attached to the barrel and extending laterally from the barrel and alongside thereof and cooperating with the contacts to separate them in one position of the barrel, and a metal rivet carried by the plate for bridging the blades in another position of the barrel.

6. A lock switch comprising, a switch case, a lock barrel slidably supported by the case, terminal brackets within the case, a pair of spring blade contacts attached to the back wall of the case and extending toward the front wall and alongside the barrel, and a member attached to the barrel and extending laterally from the barrel and alongside the barrel and cooperating with the blade contacts to open and close an electric circuit.

7. A lock-switch comprising, a switch case, a lock barrel slidably supported by the case, terminal brackets within the case, contacts attached to the brackets and extending alongside the barrel, and a member attached to the barrel and extending laterally from the barrel and alongside the barrel and cooperating with the blade contacts to open and close an electric circuit.

8. A lock-switch comprising, a switch case, a lock barrel slidably supported by the case, terminal brackets within the case, contacts attached to the brackets and extending alongside the barrel, a non-conducting plate attached to the barrel and extending laterally from the barrel and alongside thereof and cooperating with the contacts to separate them in one position of the barrel, and a metal rivet carried by the plate for bridging the blades in another position of the barrel.

9. A lock-switch comprising, a switch case, a lock barrel slidably supported by the case, terminal brackets within the case and attached to the back wall thereof, contacts attached to the brackets and extending alongside the barrel, and a member attached to the barrel and extending laterally from the barrel and alongside the barrel and cooperating with the blade contacts to open and close an electric circuit.

10. A lock-switch comprising, a switch case, a lock barrel slidably supported by the case, a spring bearing against a wall of the

case and the end of the barrel within the case for urging the barrel in one direction, a key controlled latch for holding the barrel in one position against the force exerted by the spring, a pair of spring blade contacts attached to the back wall of the case and extending toward the front wall and alongside the barrel, and a member attached to the barrel and extending laterally from the barrel and alongside the barrel and cooperating with the blade contacts to open and close an electric circuit.

11. A lock switch comprising in combination, a case, a lock barrel slidably supported by the case, a spring bearing against a wall of the case and the end of the barrel to urge the barrel in one direction, a key controlled latch for holding the barrel in a position against the force of the spring, relatively fixed switch contacts carried by the case and extending alongside the barrel, a switch actuator attached to said barrel and extending alongside of the barrel and carrying a switch contact for bridging the relatively fixed contacts.

12. A lock switch comprising in combination, a switch case having a back wall and a front wall, a lock barrel slidably supported by the front wall, a plurality of spring blade contacts attached to the back wall of the case and extending toward the front wall and alongside the lock barrel, and a member attached to the barrel and extending laterally therefrom and alongside thereof and cooperating with the blade contacts to open and close electric circuits therethrough.

13. A lock switch comprising in combination, a case provided with a nonconducting end wall, conducting brackets mounted upon said nonconducting wall and providing switch contacts, a frame closing an end of the case and providing a tubular bearing, a lock barrel and switch actuating means slidably supported by said tubular bearing, said switch contacts extending toward said frame and alongside the tubular bearing, a nonconducting plate attached to the barrel and carrying a bridging contact for engagement with said switch contacts.

14. A lock switch comprising a case, a lock barrel and switch actuating means slidably supported by the front wall of the case, a group of spring blade contacts attached to the back wall of the case and extending toward the front wall and alongside the switch actuating means, said contacts being closely grouped about a central point, a nonconducting plate actuated by the barrel and extending into the central point and cooperating with the contacts to separate them in one position of the barrel and a movable contact carried by said plate operable to coincidentally connect all of said contact blades in another position of said barrel.

15. A lock switch comprising in combina-

tion, a case, a lock barrel and switch actuator slidably supported by the front wall of said case, a group of spring blade contacts arranged in juxtaposed position about a central point at one side of said lock barrel, and a member actuatable by said lock barrel and movable into the central point longitudinally of said spring blade contacts, said member providing means for opening and closing electric circuits through said spring blade contacts.

In testimony whereof I hereto affix my signature.

HARRY E. NORVIEL.
